UNITED STATES PATENT OFFICE

GEORGE PRIFOLD, OF LINWOOD, PENNSYLVANIA, ASSIGNOR TO THE CONGOLEUM COMPANY, OF PHILADELPHIA, PENNSYLVANIA, A CORPORATION OF PENNSYLVANIA.

PROCESS OF PRINTING RUGS.

1,191,824.

Specification of Letters Patent. Patented July 18, 1916.

Application filed February 28, 1916. Serial No. 80,879.

To all whom it may concern:

Be it known that I, GEORGE PRIFOLD, a citizen of the United States, and a resident of Linwood, county of Delaware, State of Pennsylvania, have invented certain Improvements in Processes of Printing Rugs, of which the following is a specification.

One object of my invention is to improve the process of printing rugs, or other bordered materials.

A further object of the invention is to so arrange the blocks of a block printing machine for printing rugs that the outline of the border will be formed on one or more sets of blocks and the covering design for the material will be formed on another block or blocks, according to the number of colors used in printing the rug.

Prior to my invention the design of the rug was formed on each block of the block printing machine, including the border designs, necessitating the use of, at least, three blocks for each color. By my invention, I can use three blocks for the outline design of the border and a single block for each additional color of the cover design. The term "cover design" means that it is the design used to cover the base of the material, as in printing oilcloth, and like material, it is desirable to cover as much of the surface of the base material as possible in order to increase the wearing qualities of the printed material.

In the accompanying drawings: Figure 1 is an inverted plan view of one end of the end border blocks of a block printing machine; Fig. 2 is an inverted plan view of the other end border block; Fig. 3 is an inverted plan view of the block having the intermediate border design thereon; Fig. 4 is an inverted plan view of one of the cover blocks; Fig. 5 is a view of a rug printed with the blocks illustrated in Figs. 1 to 4 inclusive, and Fig. 6 is a view of a portion of the rug printed with a modification of the blocks, in which the design runs through the lines of the border, as well as through the body of the rug.

In the drawings, I have illustrated the blocks and the designs on the rug in diagram, as it will be understood that the blocks consist of a number of small projecting elements, which print dots or lines on the material.

My invention is adapted to be used in

connection with the block printing machine covered by Letters Patent No. 1,145,821, granted to William H. Waldron on the sixth day of July, 1915, but it will be understood that it can be applied to other machines without departing from the essential features of the invention.

Referring to the drawings, 1 is a block on which the design for the left hand end of the border is formed.

2 is a block on which the right hand end of the border is formed and 3 is a block on which the sides of the border are formed and preferably a center design 4 which corresponds to the end border lines 5 of the blocks 1 and 2. The side border lines 6 of the blocks 1 and 2 align with the side border lines 6^a of the block 3, so that when an impression is made by the several blocks, as illustrated in Fig. 5, a complete border is formed and the center design 4 extends across the rug at equal distances from each other and past the side border lines 6^a. It will be understood that the blocks 2 and 3 may have other designs, such as 9 thereon, which are of the same color as the border designs.

I have only illustrated one cover block 7 having a design 8 thereon. This design, when impressed on all four sections of the rug, as in Fig. 5, alternates with the border and other designs printed by the blocks 1, 2 and 3, giving an ornamental effect which extends throughout the rug and into the border. It will be understood that in practice two or more of these cover blocks 7 will be used, according to the number of colors with which it is desired to print the rug, and, as hereinbefore stated, it is preferable to make the design so that the entire surface of the material will be substantially covered by the printed design.

In Fig. 5, the cover design does not extend into the lines of the border, the lines being made plain in this instance. They may, however, extend into the border, forming an ornamental feature of the border, as in Fig. 6, the border being what may be termed a "shadow" border, which is not so prominent as where the lines are clear, as in Fig. 5.

One of the blocks instead of having a "set" figure, as illustrated in Fig. 4, may have a "running" figure, which will extend through the entire rug and the design formed by

the printing blocks may be varied as fancy and requirements dictate.

By forming the blocks in the manner above described, I am enabled to print elaborate designs in many colors on a comparatively small block printing machine, where the number of blocks is limited, as I dispense with two blocks of a series for each color, heretofore found necessary in printing rugs.

I claim:

1. The process herein described of manufacturing a printed rug, said process consisting in providing two or more blocks to print the complete border and providing two or more cover blocks having designs thereon registering with the border designs so that a single cover block for each color can be used for printing the border and the body of a rug.

2. The process herein described of manufacturing printed rugs, said process consisting in providing three printing blocks, one of the series of three blocks having a right hand border design thereon, another block having a left hand border design thereon,

and the third block having the intermediate side border design thereon, and providing one or more cover blocks having a cover design thereon which will register with the designs on all three of the first mentioned blocks so that a border design will be printed with the first three mentioned blocks to outline the rugs, while the fourth block will print a cover design on the surface receiving the impressions from all three of the first mentioned blocks.

3. The process herein described of manufacturing printed rugs, said process consisting in providing a series of three printing blocks, one block having a right hand border design thereon, the other block having a left hand border design thereon; and a third block having a portion of the body design and a continuation of the border design thereon; and a block having a design thereon so spaced that it will print on each side of the border design and will also register with the design for the body of the rug printed by the first mentioned blocks.

GEORGE PRIFOLD.
